UNITED STATES PATENT OFFICE.

CHARLES HEIMAN, OF PHILADELPHIA, PENNSYLVANIA.

PIVOTED AND SLIDING WINDOW SASH.

Application filed January 16, 1926. Serial No. 81,654.

My invention relates to a window sash and is intended particularly to facilitate washing the glass of the sash.

The purpose of my invention is to provide a pivoted window sash within a normal sliding sash so that the pivoted sash may be reversed in position for washing purposes.

A further purpose is to mount the glass of a window directly in a pivoted sash carried by a sliding sash and to protect the joint between the pivoted sash and its mount by a vent frame.

Further purposes will appear in the specification and in the claims.

I have preferred to illustrate my invention by but one main form, with slight modifications, selecting a form which is practical, efficient and inexpensive and which at the same time well illustrates the principles of my invention.

Describing the figures of the drawing:—

Figure 1 is an inside elevation of a window frame in which are located two of my sashes.

Figures 2 and 3 are sections of Figure 1 upon lines 2—2 and 3—3 respectively.

Figures 4 and 5 are a fragmentary inside elevation and a section upon line 5—5 thereof showing a modification.

Figures 5^a and 5^b are fragmentary sections corresponding generally with Figure 5 but showing a further slight modification.

Figure 6 is a fragmentary enlarged section of Figure 3.

In the drawings similar numerals indicate like parts.

My invention is intended to relieve the difficulties and dangers attendant upon the washing of windows in existing sliding sashes where the windows cannot be reached from the ground. It avoids the necessity for leaning out of the window to clean the glass and permits cleaning from the inside free from interference by weather conditions and without chilling of the room during the cleaning.

I show a casing 7 provided with the normal sash channels 8 and 9 between the outer and inner guide strips 10 and 11 and the middle guide strip 12.

Within these guides fit the sliding sashes 13 and 14 which perform the same function and bear the same relation to the casing as the normal sliding sashes in any window.

Within the sliding sashes I provide openings 15, 16 within which are located pivots 17, 18 shown at the middle of the top and bottom of the openings in Figures 1-3 and at the middle of the sides in Figures 5 and 6. These support inner pivoted sashes 19 and 20 in which the glass 21 is secured at 22. So far as described and as best seen in Figures 1-5, this leaves the pivoted sashes free to turn upon their axes so as to reverse the sashes and to make both sides of the glass readily accessible for cleaning. If the pivots be central—whether they be mounted upon the fixed or movable parts—the inner and outer faces 23 and 24 of the pivoted sashes will align equally with the sliding sashes making the pivot sashes interchangeable in their two positions except for the placing and fastening of the glass. On the other hand deliberate eccentric mounting of the pivot will prevent complete turning of the sashes and thus ensure that the intended outside face of the glass is always directed outwardly when the sashes are closed. The outer faces of the sashes are slightly curved.

Whatever the fact as to the pivoted sashes aligning with the sliding sashes in one position only or in both positions, the cracks 25 between the pivoted sashes and the surrounding sliding sashes can be closed quickly and completely by vent frames 26 which fit against the inner sides of the pivoted sashes and also against the inwardly directed faces of the sliding sashes, closing off the crack 27 between.

The vent frames may be fastened in position within the sliding sashes by any convenient means for which I have shown snap buttons 27 in the one and openings 28 in the other. The vent frames are provided with hand engaging devices 29.

My invention is equally adapted to upper and lower sashes and applies regardless of the size or shape of the sashes.

The form shown in Figures 4 and 5 differs from that of Figures 1-3 not only in having horizontal pivoting for the swinging sashes, but also in recessing the edges of the sliding sashes so as to provide for flanges 30 upon the vent frames which cover over and additionally protect the cracks 25 between the pivoted sashes and the sliding sashes, requiring air leakage to follow a tortuous passage as distinguished from a direct passage

through. This flange and recess construction is carried throughout all four outer edges adjacent the inner faces of the sashes. At the division line between the upper and 5 lower sashes this portion 30 upon the vent frame for the upper sash can easily be fitted into the position shown in Figure 5 by sliding it in diagonally from above.

In the structure seen in Figures 5^a and 5^b 10 the swinging pivoted sashes are grooved to provide for a shoulder 31 upon the outside of one edge and upon the inside of the other edge of the adjacent sliding sashes, protecting against leakage through the cracks 15 25 though preventing completion of swinging movement of the sashes throughout the 360°. Corresponding ribs and grooves upon the outside and inside respectively are contemplated at the top and bottom so as to 20 seal in this manner throughout a large part of the distance from the respective sash sides to the pivot.

Normally the vent frame is in position as shown in the figures and each tilting sash 25 lies as seen in Figure 2. The window-panes are cleaned upon their inside faces as usual. When the outer faces are to be cleaned the vent frames are removed and the pivoted sashes are turned to face the outer faces 30 inwardly for cleaning. They are then again turned to the position shown in Figures 2 and 5 and the vent frames are replaced in position.

My invention does not interfere with the 35 use in the sliding sashes of such refinements as overlapping of one sash with respect to the other as by flanges 32, but adds a benefit not present with the sliding sashes.

It will be obvious that the vent frames

may be withdrawn in warmer weather giving the advantage of swinging the tilting sashes instead of lifting or lowering the sliding sashes securing substantially entire opening for each window.

In view of my disclosure other means of 45 securing all or a part of my invention differing from it to meet special difficulties, to satisfy a whim or merely to avoid direct copying will occur to those skilled in the art and it is my purpose therefore, to include herein all modifications and changes which come within the reasonable spirit and scope of my claims.

Having thus described my invention, what I claim as new and desire to secure by Letters Patent is:—

1. A sliding window sash, in combination with a pivoted window sash carried by it and sealing it transversely and a removable vent frame sealing the joint between them. 60

2. A sliding window sash having an opening and interiorly recessed to provide a shoulder, in combination with a sash pivoted in the opening and a wholly removable vent frame fitting against the shoulder and sealing against leakage of air between the pivoted sash and the sliding sash. 65

3. A sliding sash having an opening in it and a recess forming a shoulder adjacent the recess, in combination with a pivoted sash within the opening and normally having its inner face depressed in the sliding sash and a vent frame fitting against the inner face of the pivoted sash and the shoulder and readily movable from set position to permit reversal of the pivoted sash. 70 75

CHARLES HEIMAN.
